FREIGHT CAR LOADING APPARATUS

George M. Reifer, Rochester, Mich., assignor to
General Motors Corporation, Detroit, Mich., a
corporation of Delaware

Application March 25, 1937, Serial No. 132,932

11 Claims. (Cl. 105—369)

This invention has to do with adjustable load bracing means for holding freight in box cars and the like. It consists in the provision of stanchions, preferably of channel iron, which are 5 adjustably positioned along the side wall of the car by engaging their ends with suitable holding means arranged along top and bottom of the side walls of the car. The channel irons are adapted to receive between them adjustable braces which 10 engage the freight and prevent its shifting in the car.

The invention has to do with a cheap and simple arrangement of parts for accomplishing the above result, and is also characterized by the 15 convenience with which the desired adjustments may be made.

Figure 1 is a side view of a portion of the side wall of a freight car with one of the stanchions in place.

20 Figure 2 is an enlarged perspective view of the upper end of Figure 1.

Figure 3 is an enlarged perspective view of the lower end of Figure 1.

Figure 4 shows one of the spikes or keys which 25 may be used to hold the lower end of the stanchion in place.

30 Figure 10 indicates a sheet metal strip adapted to be secured preferably along the top of the side wall of a freight car. The upper end of the strip is formed to provide outwardly and downwardly bent tongues 12 and downwardly and outwardly bent abutments 14 alternating with the tongues. The tongues and abutments are slightly spaced as shown at 16.

35 To the bottom of the car or to the side wall adjacent the bottom is secured the notched strip 18, the notches corresponding with the tongues 12 of the strip 10. Channel iron stanchions 20 are adapted to be positioned as shown in Figure 40 2 with tongue 12 occupying the upper end of the channel and the lower end of the stanchion seated in a notch in the strip 18. The spike or key 21, shown in Figure 4, is inserted in a hole in the floor to prevent displacement of the lower end 45 of the stanchion. It will be noted from Figures 1 and 2 that the abutments 14 engage the flanges of the channel at the upper end, and assist the tongues in resisting displacement of the stanchion under the heavy forces exerted on them by the 50 freight in transit.

As indicated in Figures 1 and 2 the stanchions 20 are adapted to receive braces 22 which as shown may consist of channel iron with a wooden filler as shown. The braces 22 may be adjustably 55 supported in any desired position along the length

of the stanchion by means of pins 24 engaging aligned apertures 26 in the flanges of the channel.

The described construction obviously provides a cheap and simple method of adjustable bracing for freight car loads. It is obvious, of course, 5 that it is equally applicable to other carriers and the term "freight car" is used in the claims with this connotation. It will also be understood that the invention is capable of considerable modification as, for example, by reversing the position of 10 the top and bottom strips, and it will be understood that the terms "top," "bottom" and so on are used in a relative sense only, and not in an absolute sense.

I claim:

1. Adjustable load bracing means for freight cars and the like comprising a strip secured to a car wall and extending longitudinally thereof, said strip being provided with outwardly extending abutments and with downturned tongues 20 alternating with the abutments and spaced therefrom, a stanchion having one end adapted to be telescoped over any of said tongues, portions of said end being adapted to engage adjacent abutments to resist displacement, and means for securing the other end of the stanchions in position. 25

2. Adjustable load bracing means for freight cars and the like comprising a strip secured to a car wall and extending longitudinally thereof, said strip being provided with outwardly extending abutments and with down-turned tongues alternating with the abutments and spaced therefrom, a stanchion having one end adapted to be telescoped over any of said tongues, portions of 30 said end being adapted to engage adjacent abutments to resist displacement, a strip secured to the car wall adjacent the bottom thereof, said strip being notched to provide sockets to receive the lower ends of the stanchions and means for securing the stanchions in said notches. 35

3. Adjustable load bracing means for freight cars comprising a strip secured adjacent the top of the side of the car, said strip being provided with spaced outwardly and downwardly bent tongues, a strip secured adjacent the bottom of the side wall having notches therein corresponding with said tongues, and a channel iron stanchion adapted to receive any one of said tongues within its channel at one end thereof while the other end of the stanchion is received in the corresponding notch. 45

4. In the combination as defined in claim 3, abutments extending outwardly from the first-named strip between said tongues and spaced therefrom and adapted to engage the sides of the 50 55

- channel to prevent lateral displacement thereof.
5. Adjustable load bracing means for freight cars comprising a strip secured adjacent the top of the side of a car, said strip being provided with outwardly and downwardly bent tongues alternating with and spaced from downwardly and outwardly bent abutments, a strip secured adjacent the bottom of the side wall having notches therein corresponding with said tongues, and a channel iron stanchion adapted to receive any one of said tongues within said channel at one end thereof while the other end is received in the corresponding notch.
6. A strip for receiving stanchions for use in freight car loading comprising a longitudinally extending securing portion, tongues outwardly and downwardly bent from one edge of said securing portion alternating with and spaced from abutments extending outwardly between said tongues.
7. A strip for receiving stanchions for use in freight car loading comprising a longitudinally extending securing portion, tongues outwardly and downwardly bent from one edge of said securing portion alternating with and spaced from abutments bent downwardly and outwardly from the same edge of said securing portion.
8. Adjustable load bracing means for freight cars and the like comprising spaced lugs extending longitudinally of the car along opposite side walls thereof, said lugs including down-turned end portions extending parallel to but spaced from said walls, a pair of stanchions arranged at opposite sides of the car, each of said stanchions having its upper end formed to provide a socket and being arranged with one of
- said lugs in the socket, thereby positioning the stanchions longitudinally of the car, means for securing the lower ends of the stanchion against longitudinal displacement, and braces extending between said stanchions and holding them against inward movement.
9. In the combination as defined in claim 8, the securing means for the lower ends of the stanchions comprising a strip extending longitudinally of the car adjacent the bottoms of the side walls thereof and having notches to receive the ends of the stanchions.
10. Adjustable load bracing means for freight cars and the like comprising strips secured adjacent the tops of the opposite side walls of the car and extending longitudinally thereof, spaced tongues bent from said strip and having down-turned end portions lying parallel to but spaced from the said side walls, a pair of stanchions each having one end formed to provide a socket adapted to receive any one of said end portions to position the stanchion against longitudinal displacement, said stanchions being so positioned opposite each other along the car walls, means for securing the lower ends of said stanchions against longitudinal displacement, and a brace extending between said stanchions and holding them against inward displacement.
11. In the combination as defined in claim 10, the means for holding the lower ends of said stanchions against longitudinal displacement comprising bars extending longitudinally of the side walls adjacent the bottoms thereof and having notches to receive the lower ends of the stanchions.

GEORGE M. REIFER.
